COUPLING DEVICE

Gerald Deakin, New York, N. Y., assignor to International Standard Electric Corporation, New York, N. Y., a corporation of Delaware

Application September 13, 1946, Serial No. 696,794

5 Claims. (Cl. 192—4)

1

The present invention relates to improvements in coupling devices adapted particularly for use in driving carriages, such as brush carriages of selector switches, for example switches of this character used in automatic telephone systems as finder switches, group selectors, final connectors, marking switches or the like.

More particularly, this invention applies to improvements in switches wherein the drive between two shafts is effected by means of a gear fixed on one of said shafts and a flexible gear which when flexed is disconnected from the other gear and, when released by an electromagnet, meshes therewith.

An important feature of the invention is to provide a novel and advantageous disengageable gear drive of the general character specified.

Another object of the invention, is to provide a novel and advantageous magnetic circuit more powerful than those heretofore in use.

Still another object of the invention is to provide a novel and advantageous gear drive of the type specified equipped with a more powerful and more rapid magnetic circuit.

Yet another object of the invention is to provide a novel electromagnetic apparatus wherein the pressure is symmetrically applied to the armature.

A further object of the invention is to provide a coupling device operated by an electromagnet and enabling more accurate control of the air gap.

A further object of the invention is to provide a magnet of the character described wherein the armature has a universal pivotal mounting.

A still further object is to provide a disengageable gear drive of the general character specified wherein an electromagnetic operating unit is readily mounted or demounted.

Other objects, features and advantages will appear upon consideration of the following detailed description and of the drawings, in which:

Fig. 1 is a fragmentary top plan view of apparatus embodying one form of the invention.

Fig. 2 is an elevation of the structure shown in Fig. 1, and

Fig. 3 is a fragmentary end view illustrating the supporting means for the magnet and associated parts illustrated in Figs. 1 and 2.

Referring to the drawings, a U-shaped core 10 of a horseshoe magnet 11 is secured to a plate or flat portion 12 of a frame 13 by suitable means such as a screw 14 passing through a raised portion 15 of the plate 12 and threaded into the leg-connecting part of said U-shaped core. Said

2

raised portion 15 of the plate 12 may be formed between two parallel cuts 16 and provides at the other face of the plate a recess which receives the base of said U-shaped core. Said core 10 is illustrated as having legs 17 on which are mounted coils 18 of corresponding cross section.

At the right of plate 12, the frame 13 comprises an arm 19 comprising a central extension 20, a downturned portion 21, and at the lower end of said downturned portion 21, an outturned portion 22.

Projecting upwardly through an internally threaded bore in said extension 20 is the threaded end of the shank of a bolt 23 having at its lower end a rounded head 24 bounded by a spherical surface and fitting into a corresponding recess 25 in an armature 26 having a broad end adjacent to the poles 27 at the lower ends of said legs 17.

20 Said rounded head 24 and recess 25 of the armature 26 provide what may be called a universal pivotal support for the armature 26 which enables the armature to adjust itself for proper engagement with said poles 27. Obviously 25 the illustrated form of universal support comprises a ball and socket joint. The pivotal support for the armature can readily be adjusted by turning said bolt 23 in said extension 20. Upon completion of an adjustment the bolt may 30 be locked in adjusted position by means of a lock nut 28.

The armature 26 is used to control in a known manner, the connection between a thin flexible gear 29 fixed to a shaft 30 to turn therewith, and a thin driving gear 31 fixed on a driving shaft

35 32. The flexible gear 29 is tensioned so that if free of control it will mesh with gear 31 and press lightly against a disk 33 at the lower face of gear 31 and fixed with relation thereto. The armature 26 has an arm 34 extending beneath said flexible gear 29 and provided at its end beneath said gear with a control member 34a having a flat top.

The armature arm 34 is urged upwardly by 45 suitable means comprising a helical spring 35 having at its lower end a hook engaging a cross pin or member 36 of said arm 34 formed by providing at opposite sides thereof openings through the armature arm. Said spring 35 is enclosed in a tubular member 37 of which the lower end is externally screw threaded and is screwed into an internally threaded opening in portion 22 of frame 13. At its upper end the spring 35 is provided with a hook 38 which is caught over a pin 50 39 resting on the top of said tubular member 37.

Above the screw threaded lower end of tubular member 37 there is a part 40, preferably with a hexagonal cross section, adapted for engagement by a wrench or the like. The tension of the spring may be adjusted by screwing the tubular member 37 up or down and then locking it in adjusted position by means of a lock nut 41.

While the magnet 11 is deenergized, the spring 35 will hold the flexible gear 29 in flexed condition and pressed against a flat-end control member 42 with a head in the form of a nut, adjustably secured in outturned portion 22 of arm 19, as by being screwed through an opening in portion 22. At this time the flexible gear 29 will be gripped between the control members 34a and 42. Obviously the control member 42 serves to limit the flexing of the flexible gear and in cooperation with the control member 34a provides a brake to stop and hold the flexible gear against rotation. Upon energization of the magnet 11, as a result of starting a call or dialing, the armature arm 34 is swung downwardly. The flexible gear then meshes with driving gear 31 and shaft 30 is driven from shaft 32.

The shaft 30 may be utilized to drive a brush carriage in the general manner described in my Patent No. 2,490,035.

It is important to be able to mount such electromagnetic devices readily and also to demount them readily. To this end, the bracket 13 is narrowed at the left of flat portion 12 to a parallel sided portion slightly to the front of the center line of part 12 and this portion is turned downwardly to provide a vertical support or leg 45. A machine screw 46 with a suitably formed operating head is screwed into said leg 45 from the outer side thereof. On the shank of said screw 46 is a washer 47. At its right and to the front of part 18, the flat portion 12 is provided with a downturned leg 48 somewhat longer than leg 45. Threaded into leg 48 from the right are screws 49 positioned at levels above and below that of screw 46. Each screw 49 is provided with a washer 50.

Each frame 13 may be supported by a bracket or clip 51 of generally U-shape of which the base is secured to a support 52 at a vertical side thereof, and arms 53 and 54 at the same general level extend forwardly from said support. The arm 53 shown at the left in Figs. 1 and 2 and at the front in Fig. 3, is narrowed to a parallel sided portion provided at its end with a slot 55 into which the shank of screw 46 is inserted, the washer 47 being kept next to the head of the screw. The arm 54, shown at the right of Figs. 1 and 2 and at the rear in Fig. 3 is of the same width throughout its length and is longer than arm 53 so that the shanks of screws 46 may enter slots 56 in the end of said arm and be secured therein by tightening nuts 49.

As indicated in Fig. 1, brackets 51 may be provided at the back of support 52, and corresponding disengageable gear drives may be mounted at the rear of the support. With this arrangement, another flexible gear would be supplied at the rear and would be driven by gear 31 in a similar manner. As indicated in Fig. 2, the armature 26 may be provided with a suitable shield 57 of nonmagnetic material such as phosphor bronze to engage the pole pieces provided at the ends of legs 17 of the magnet core 10 and prevent freezing as well as determine the effective air gap between armature 26 and said pole pieces. Upon energization of the magnet as by starting a call, the armature will swing about the

rounded head of the bolt 23 and at the same time the armature will adjust itself so as to engage both legs of the magnet core, thus enabling the magnet to act with greater force and speed. Concomitantly, the right end of the armature (Fig. 2) will swing downwardly thus releasing the flexible gear 29 which will then mesh with the gear 31 and be driven thereby. The shaft 30 will then be operated and in turn, will drive a selector carriage in a suitable manner, for example as shown in said applications referred hereinbefore.

Upon completion of an operation such as finding a free terminal, the magnet would be deenergized thus permitting the spring 35 to operate the armature in the opposite direction, thereby flexing the flexible gear 29 out of mesh with driving gear 31 and stopping the brush carriage.

It should be noted that the tubular member 37 enclosing the helical spring 35 limits lateral swing of said spring, thus assisting in maintaining the armature in operative relation with the magnet 11 and the flexible gear 29.

It should be understood that various changes may be made and that certain features may be used without others, without departing from the true scope and spirit of the invention.

What is claimed is:

1. Coupling device comprising in combination, a driving gear, a driven flexible gear normally in operative engagement with said driving gear, and means for selectively deflecting said flexible gear out of engagement with said driving gear and preventing rotation of said flexible gear during such deflection comprising an electromagnet, a frame member supporting said electromagnet, a fulcrum member extending from said frame member, a rounded head for said fulcrum member, an armature for said electromagnet, a rounded socket in said armature for receiving said rounded head of said fulcrum member to pivot thereon, a brake member fixed with respect to said frame member, and having a braking surface in spaced juxtaposed position with respect to said flexible gear, a second brake member mounted on said armature and disposed on the opposite side of said flexible gear with respect to said first brake member and having a brake surface complementary to the brake surface of said first brake member, means attached to said armature and adapted to bias said armature with respect to said frame about said fulcrum in such a direction as to force the brake surface of the second brake member toward said brake surface of said first brake member thereby forcing the flexible gear out of engagement with the driving gear and clamping the flexible gear between the braking surfaces to prevent rotation thereof, and circuit means associated with said electromagnet for energizing said magnet to attract said armature to overcome said bias and to permit the flexible gear to return to engaging position with respect to said driving gear.
2. A coupling device comprising a driving gear, a flexible driven gear normally in engagement therewith, an electromagnet, a frame member supporting said electromagnet, an armature, a brake having a pair of complementary braking surfaces, one of said surfaces being mounted in a fixed position with respect to said frame member, the other of said surfaces being supported on said armature, said brake surfaces being arranged on opposite sides of said flexible driven gear at a point thereof in close proximity to the point of engagement of said driven gear with said driving

70
75

gear so as to permit free rotation of said flexible driven gear when said second surface is in spaced position with respect to said first surface and adapted to flex, the driven gear out of engagement with said driving gear when said second surface is forced toward said first surface and to prevent rotation of said driving gear, biasing means for normally biasing said second surface toward said second surface, means for providing proper orientation of said armature with respect to said electromagnet and said first brake surface comprising a universal fulcrum means for said armature fixed with respect to said frame member, and circuit means for energizing said electromagnet to attract one end of said armature to cause said armature to pivot on said universal fulcrum and overcome said bias to release said brake and permit engagement of said flexible driven gear with said driving gear.

3. A device according to claim 2 wherein said fulcrum means comprises a ball-and-socket joint.

4. A device according to claim 2 wherein said fulcrum means comprising a fulcrum member extending from said frame member and provided with a rounded head, said armature having a

rounded depression receiving said head and forming a ball-and-socket type joint therewith.

5. A device according to claim 4 wherein said fulcrum member comprises a rod having the end opposite said head adjustably threaded into said frame member.
